Specification of Letters Patent.

Patented Jan. 13, 1914.

Application filed February 25, 1911. Serial No. 610,682

To all whom it may concern:

Be it known that we, EDWARD B. HESS, of the borough of Manhattan, city, county, and State of New York, and LEWIS C. MYERS, of the borough of Brooklyn, county of Kings, and State of New York, citizens of the United States of America, have invented a certain new and useful Improvement in Type-Writing Machines, of which the following is a specification.

This invention relates to visible writing machines, particularly to front strike machines, wherein the type bars are actuated by key-lever-operated links movable toward the front of the machine to pull the type bars to the printing point.

The invention is comprised in the organization hereinafter set forth in detail, and is an improvement upon the construction shown in our Patent No. 831,511 of September 18, 1906.

In the accompanying drawing: Figure 1 is a plan view, with some of the type bars omitted, of so much of a front strike type-writing machine as is thought to be desirable to illustrate the invention; Fig. 2, a front view with some parts omitted and some broken away; Fig. 3, a vertical longitudinal section showing the left hand side plate of the machine; Figs. 4, 5, 6 and 7 are detail views showing the different lengths of key levers and type bar actuating links with which they are connected; and Fig. 8, a detail plan showing the jointed type bar actuating links at the center of the machine.

The platen 1 is mounted in carriage 2.

3 is the carriage shift rail by which the carriage is elevated for upper case printing. Between the side plates 4, 4 of the machine is supported a vertically disposed type bar segment 6, of appropriate construction, in which are pivoted the type bars 7 that normally lie in a substantially horizontal position with their heads toward the front of the machine and upon a rest 8. Each type bar has connected to its heel, or the projection beyond its pivot, a draw link 9 that extends forwardly under the assemblage of type bars and at its front end has a hinge connection with a shorter link mounted to rock about a fixed axis 11. These shorter lever-links 10, 10' are connected intermediate their ends by vertically disposed links 12 that extend downwardly to their respective key levers

13 which are pivoted on a common transverse pivot rod 14 disposed below the assemblage of type bars.

15 indicates the universal bar movable fore-and-aft of the machine as in the Royal Standard typewriting machine and from the type bar operating links 9 there extend draw links 16 having hooked ends that embrace the universal bar. Surrounding each link 16 is a coiled spring 17 having its front end connected to a clip by which the link 16 is connected to the type bar link 9 and its rear end connected in a plate 18 attached to the back plate of the machine.

The special features of construction or arrangement embodying the present invention are as follows: The key levers 13 comprise four series arranged in the key board in four rows as usual. Those of each row therefore differ in length from those of all other rows. 75 They are, however, all relatively short in that their common pivot rod 14 is located well in front of and below the type bar segment. The common axis 11 for the plurality of lever-links 10, 10' is afforded by a transverse casting or bar 19 having on its upper face at each end upwardly extending ribs 20 to give it rigidity and insure that the axes of the links 12 shall be maintained in a straight transverse line across the front of 80 the machine. The part 19 is slotted on its under face to form bearing slots for the respective lever-links 10, 10'. The partitions or flanges 21 have bored or cut in them transversely of the machine in a straight line a 85 seat 21' for a common pivot rod 11 that forms the axis or bearing for all the front lever-links 10, 10'. This rod is inserted endwise, apertures 11' being formed in one or both side plates for that purpose. The front 90 lever-links 10, 10' extend rearwardly, those in the center being at right angles to the axis 11 and those at each side being, with gradually increasing angle, turned toward the center of the machine. The whole assemblage of lever-links is divided into two series, the links of one series being marked 10 and the shorter links of the other series being marked 10'. These longer and shorter levers are arranged in alternation. As seen 100 in Fig. 8, this results in a staggering of the connections between the lever-links and the type bar operating links 9. The latter may be merely hooked into apertures in the former,—yet by reason of the staggering of the 110

ends of the front lever-links there is ample clearance. The key levers are straight and lie throughout their length in parallel straight lines at right angles to their axis 14. The shortest and next longer key levers whose finger pieces *a*, *b*, are in the two upper or most rearward rows in the key board are connected by vertically disposed links 12 to the longer front lever-links 10; and the next 10 longer and the longest key levers, whose finger pieces *c*, *d*, are in the two lower or most forward rows in the key board, are connected with the shorter front links 10'.

As may be seen from Fig. 3, the longer 15 front lever-links 10 are inclined rearwardly and downwardly from their fixed axis 11 and the shorter lever-links 10' are similarly inclined but have a somewhat greater downward inclination from a horizontal plane.

20 All the short lever-links 10' are inclined downwardly at a uniform angle; and all the longer lever-links are also inclined downwardly at a different, but uniform, angle. To procure substantially uniform 25 depth of depression and approximately uniform "touch" of all the finger pieces of the key board, the following plan is adopted. The shorter key levers, whose finger pieces *a* are in the rear row of the key board, are 30 each connected to one of the longer lever-links 10 (Fig. 4) by a link 12 extending upwardly from the corresponding key lever, the points of connection of the substantially vertical link to the lever-link 10 and to the 35 key lever being such as to afford a desired extent of depression of the finger piece *a* to throw the type bar to the printing point. The next longer key levers whose finger pieces *b* are in the second row from the rear 40 in the key board are also each connected (Fig. 5) to a long lever-link 10 by a link 12; but the point of connection of the latter link to the link 10 is nearer the fixed axis 11 than is the corresponding substantially vertical link connection of the shortest key 45 lever. In both instances the points of connection of the vertically disposed links 12 with the key levers are at the same distance from the fixed axis 14 of the key levers. 50 The relationship of parts and leverages is such that the finger pieces *a*, *b*, have the same extent of depression and substantially the same "touch." The next longer key levers whose finger pieces *c* are represented 55 in the second row from the front of the key-board are each connected to one of the shorter front links 10', as in Fig. 6. The distances from the axis of the short links 10' and from the axis of the key lever at which 60 the connections of links 12 are made is such as to afford a depth of depression of the finger piece the same as that for the finger pieces *a*, *b*, and also substantially the same "touch."

65 Fig. 7 shows one of the longest key levers

whose finger pieces *d* are represented in the front row of the board. Each such lever is connected to one of the shorter links 10' by a substantially vertical link 12. The connection of the latter link to the front link 10' is nearer the fixed axis 11 thereof than is the case in Fig. 6. The finger piece *d* has the same extent of depression as the others and substantially the same "touch."

70 Fig. 8 shows in plan the arrangement of 75 the two series of links 10, 10' in alternation, the links shown being those at the center of the machine. This staggering of the ends of the lever-links 10, 10' with reference to a straight transverse line affords ample room for the hooks or other means of engagement 80 on the draw links 9 by which they are attached to the lever-links 10, 10' so that in the operation of the machine one cannot interfere or collide with another.

85 We claim:

1. In a front strike typewriting machine, the combination of a platen, a type bar segment in front of and below the platen, type bars pivoted therein and normally lying 90 with their heads toward the front of the machine, two series of lever-links pivoted upon a common fixed axis transverse to the machine in front of the type bar heads, the lever-links of one series being longer than those of the other and those of the two series being arranged in alternation, type bar operating links extending from the ends of the various lever-links to the heels of the type bars, key levers of four different lengths pivoted on a common axis, substantially vertically disposed links connecting the key levers of the two shorter lengths with the longer lever-links intermediate the ends of the latter and the key levers of the two longer 100 lengths with the shorter lever-links intermediate the ends of the latter, the distances from the common axis of the lever links of the points of connection of the substantially vertical links to them varying according to 105 the length of said key levers, those of the shortest key levers being farther from said axis than are those of the key levers next in length and those of the longest key levers being nearer to said axis than are those of 110 the key levers next in length.

2. In a front strike typewriting machine, the combination of a platen, a type bar segment in front of and below the platen, type bars pivoted therein and normally lying 120 with their heads toward the front of the machine, two series of lever-links pivoted upon a common fixed axis transverse to the machine in front of the type bar heads, the lever-links of one series being longer than 125 those of the other and those of the two series being arranged in alternation, type bar operating links extending from the ends of the various lever-links to the heels of the type bars, key levers of four different lengths, 130

3 pivoted on a common axis, substantially vertically disposed links connecting the key levers of the two shorter lengths with the longer lever-links intermediate the ends of the latter and the key levers of the two longer lengths with the shorter lever-links intermediate the ends of the latter, the distances from the common axis of the lever-links of the points of connection of the vertical links to them varying according to the length of said key levers, those of the shortest key lever being farther from said axis than are those of the key levers next in length and those of the longest key levers being nearer to said axis than are those of the key levers next in length, the points of connection of the substantially vertical links to the key levers of the two shorter lengths being at a uniform distance from the common axis of the key levers and the corresponding connections of the vertical links to the key levers of the two longer lengths being also at a uniform distance from the common axis of the key levers.

25 3. In a front strike typewriting machine, the combination of a platen, a type bar segment in front of and below the platen, type bars pivoted therein and normally lying with their heads toward the front of the machine, two series of lever-links pivoted upon a common fixed axis transverse to the machine in front of the type bar heads, the lever-links of one series being longer than those of the other and those of the two series being arranged in alternation, type bar operating links extending from the ends of the various lever-links to the heels of the type bars, key levers of four different lengths pivoted on a common axis located beneath the type bars, substantially vertically disposed links connecting the key levers of the two shorter lengths with the longer lever-links intermediate the ends of the latter and the key levers of the two longer lengths with the shorter lever-links intermediate the ends of the latter, the distances from the common axis of the lever-links of the points of connection of the substantially vertical links to them varying according to the length of said key levers, those of the shortest key levers being farther from said axis than are those of the key levers next in length and those of the longest key levers being nearer to said axis than are those of the key levers next in length.

40 4. In a front strike typewriting machine, the combination of a platen, a type bar segment in front of and below the platen, type bars pivoted therein and normally lying with their heads toward the front of the machine, two series of lever-links pivoted upon a common fixed axis transverse to the machine in front of the type bar heads, the lever-links of one series being longer than those of the other and those of the two series being

45

50

55

60

65

arranged in alternation, type bar operating links extending from the ends of the various lever-links to the heels of the type bars, key levers of four different lengths pivoted on a common axis located beneath the type bars, substantially vertically disposed links connecting the key levers of the two shorter lengths with the longer lever-links intermediate the ends of the latter and the key levers of the two longer lengths with the shorter lever-links intermediate the ends of the latter, the distances from the common axis of the lever links of the points of connection of the substantially vertical links to them varying according to the length of said key levers, those of the shortest key levers being farther from said axis than are those of the key levers next in length and those of the longest key levers being nearer to said axis than are those of the key levers next in length, the points of connection of the substantially vertical links to the key levers of the two shorter lengths being at a uniform distance from the common axis of the key levers and the corresponding connections of the vertical links to the key levers of the two longer lengths being also at a uniform distance from the common axis of the key levers.

5. In a front strike typewriting machine, the combination of a platen, a type bar segment in front of and below the platen, type bars pivoted therein and normally lying with their heads toward the front of the machine, two series of lever-links pivoted upon a common fixed axis transverse to the machine in front of the type bar heads, the lever links of one series being longer than those of the other and those of the two series being arranged in alternation and inclining rearwardly and downwardly with the shorter link-levers at a greater angle of inclination than the longer ones, type bar operating links extending from the ends of the various lever-links to the heels of the type bars, key levers of four different lengths pivoted on a common axis, substantially vertically disposed links connecting the key levers of the two shorter lengths with the longer lever-links intermediate the ends of the latter and the key levers of the two longer lengths with the shorter lever-links intermediate the ends of the latter, the distances from the common axis of the lever-links of the points of connection of the substantially vertical links to them varying according to the length of said key levers, those of the shortest key levers being farther from said axis than are those of the key levers next in length and those of the longest key levers being nearer to said axis than are those of the key levers next in length.

6. In a front strike typewriting machine, the combination of a platen, a type bar segment in front of and below the platen, type 13

bars pivoted therein and normally lying with their heads toward the front of the machine, two series of lever-links pivoted upon a common fixed axis transverse to the machine in front of the type bar heads, the lever-links of one series being longer than those of the other and those of the two series being arranged in alternation and inclining rearwardly and downwardly with the shorter link-levers at a greater angle of inclination than are the longer ones, type bar operating links extending from the ends of the various lever-links to the heels of the type bars, key levers of four different lengths pivoted on a common axis, substantially vertically disposed links connecting the key levers of the two shorter lengths with the longer lever-links intermediate the ends of the latter and the key levers of the two longer lengths with the shorter lever-links intermediate the ends of the latter, the distances from the common axis of the lever links of the points of connection of the substantially vertical links to them varying according to the length of said key levers, those of the shortest key lever being farther from said axis than are those of the key levers next in length and those of the longest key levers being nearer to said axis than are those of the key levers next in length, the points of connection of the substantially vertical links to the key levers of the two shorter lengths being at a uniform distance from the common axis of the key levers and the corresponding connections of the vertical links to the key levers of the two longer lengths being also at a uniform distance from the common axis of the key levers.

7. In a front strike typewriting machine, the combination of a platen, a type bar segment in front of and below the platen, type bars pivoted therein and normally lying with their heads toward the front of the machine, two series of lever links pivoted upon a common fixed axis transverse to the machine in front of the type bar heads, the lever links of one series being longer than those of the other and those of the two series being arranged in alternation, type bar operating links extending from the ends of the various lever links to the heels of the type bars, pivoted key levers of different lengths pivoted on a common axis, substantially vertical links connecting the key levers of the shorter lengths with the longer lever links intermediate the ends of the latter and the key levers of the longer lengths with the shorter lever links intermediate the ends of the latter, the distances from the common axis of the lever links of the points of connection of the substantially vertical links to them varying according to the length of said key levers.

8. A typewriting machine of the general character described, comprising the com-

bination with alternated long and short downwardly and rearwardly inclined front lever links of rearwardly extending type bar operating links flexibly connected thereto, whereby the lever links may be kept close together and clearance afforded for the connections of the type bar links thereto, and a transversely arranged support on which the lever links are pivoted.

9. A typewriting machine of the general character described, comprising the combination with alternated long and short downwardly and rearwardly inclined front lever links of rearwardly extending type bar operating links flexibly connected thereto, a straight transverse bar in which the front ends of all the lever links are pivoted, key levers located below said links and links connecting the respective key levers with their corresponding lever links.

10. A typewriting machine of the general character described, comprising the combination with alternated long and short downwardly and rearwardly inclined front lever links, the shorter ones of which have a greater downward inclination than the longer ones, of rearwardly extending type bar operating links, flexibly connected thereto.

11. A typewriting machine of the general character described, comprising the combination with alternated long and short downwardly and rearwardly inclined front lever links, the shorter ones of which have a greater downward inclination than the longer ones, of rearwardly extending type bar operating links flexibly connected thereto and a transversely arranged support on which the lever links are pivoted.

12. A typewriting machine of the general character described, comprising the combination with alternated long and short downwardly and rearwardly inclined front lever links, the shorter ones of which have a greater downward inclination than the longer ones, of rearwardly extending type bar operating links flexibly connected thereto, key levers located below said links and links connecting the respective key levers with their corresponding lever-links.

13. A typewriting machine of the general character described comprising the combination with alternated long and short downwardly and rearwardly inclined front lever links pivoted at their front ends on coincident axes in a transverse straight line of rearwardly extending type bar operating links flexibly connected thereto.

14. In a visible writing machine the combination with the frame and type bars, normally lying with their heads toward the front of the machine of a fixed transverse bar having its under side formed with equally spaced parallel lips or flanges forming slots longitudinally of the machine, type

- bar operating links whose front ends fit in said slots and which in rear thereof are bent or displaced laterally toward the center of the machine according to their positions in 5 said bar and a pivot rod passing transversely through all the flanges and upon which all said links are pivoted.
15. In a visible writing machine the combination with the frame and type bars normally lying with their heads toward the front of the machine of a fixed transverse bar located immediately in front of the type bar heads and having its under side formed with 10 equally spaced lips or flanges forming slots longitudinally of the machine, type bar operating links whose front ends fit in said slots and a pivot rod passing transversely through all the flanges and upon which all 15 said links are pivoted.
20. 16. A typewriting machine of the general character described, comprising the combination with alternated long and short rearwardly inclined front levers of rearwardly extending type bar operating links flexibly 25 connected thereto, whereby the front levers may be kept close together and clearance afforded for the connection of the type bar links thereto.
17. In a visible writing machine the combination with the frame and type bars normally lying with their heads toward the front of the machine of a fixed transverse bar having its under side formed with parallel spaced lips or flanges forming slots 35 longitudinally of the machine, type bar operating links whose front ends fit in said slots and which in rear thereof are bent or displaced laterally toward the center of the machine according to their place in said bar 40 and a pivot rod passing transversely through all the flanges and upon which all said links are pivoted.
18. In a visible writing machine, a main frame having side plates, pivoted type bars 45 normally lying with their heads toward the front of the machine, a transverse bar secured to the side plates and formed with slots in which type bar actuating members are pivoted there being a straight aperture 50 extending through the walls of the slots of the bar and through one or both of side plates of the frame and a pivoted wire adapted to pass from the outer side of the frame through the aperture in the side plate 55 into the aperture in the bar and upon which said type-bar operating members are pivoted.
19. In a visible writing machine, the combination with the frame and type bars normally lying with their heads toward the front of the machine of a fixed transverse bar located immediately in front of the type bar heads and having its under side formed with spaced lips or flanges forming slots 60 longitudinally of the machine, type bar 65 operating links whose front ends fit in said slots and a pivot rod passing transversely through all the flanges and upon which all said links are pivoted.
20. In a visible writing machine, the combination of pivoted type bars normally lying with their heads toward the front of the machine, a transversely disposed bar arranged in a plane in front of the type bar heads, long and short lever links pivoted at 75 their front ends in said bar on coincident axes, said long and short lever links being arranged in alternation, links connecting the rear ends of the lever links with the heels of the type bars, pivoted key levers arranged below the lever links and substantially vertical links connecting the respective key levers with the respective lever links intermediate the ends of the latter, the difference in length of the two sets of lever links 80 affording clearance for the connections of the links extending from their ends to the type bars.
21. In a visible writing machine, the combination of pivoted type bars normally lying with their heads toward the front of the machine, a transversely disposed bar, long and short lever links pivoted at their front ends in said bar on coincident axes, said long and short lever links being arranged in alternation, links connecting the rear ends of the lever links with the heels of the type bars, 85 pivoted key levers arranged below the lever links, and substantially vertical links connecting the respective key levers with the respective lever links intermediate the ends of the latter, the difference in length of the two sets of lever links affording clearance for the connections of the links extending 90 from their ends to the type bars.
22. In a visible writing machine, the combination with pivoted type bars normally lying with their heads toward the front of the machine, a transverse bar arranged in a plane in front of the heads of the type bars, two sets of lever links of different 95 lengths pivoted at their front ends in said transverse bar upon coincident axes and extending rearwardly and downwardly, such longer and shorter lever links being arranged in regular alternation, links extending from the rear ends of said lever links to the heels of the type bars, key levers arranged below said links and lever links and substantially vertical links connecting the respective key levers with their corresponding lever links intermediate the ends of the latter.
23. In a visible writing machine, the combination with pivoted type bars normally 100 lying with their heads toward the front of the machine, a transverse bar arranged in a plane in front of the heads of the type bars, two sets of lever links of different lengths 105 pivoted at their front end in said transverse 110 bar.

bar upon coincident axes and extending rearwardly and downwardly, such longer and shorter lever links being arranged in regular alternation, links extending from the rear ends of said lever links to the heels of the type bars, key levers pivoted in front of the type bar pivots and arranged below said links and lever links and substantially vertical links connecting the respective key levers with their corresponding lever links intermediate the ends of the latter.

24. In a visible writing machine, pivoted type bars normally lying with their heads toward the front of the machine, a transverse bar, lever links pivoted at their front end in said transverse bar upon axes in a straight, transverse line with the pivoted portions of the links in a plane at right angles to the axis, the rear portion of the several links on each side of the longitudinal center of the machine being displaced laterally toward the center of the machine at angles which increase as the ends of the transverse bar are approached, links connecting the rear ends of the lever links and the heels of the type bars, pivoted key levers arranged in parallel series at right angles to the axis of the lever links and substantially vertical links connecting the respective key levers with the corresponding lever links.

25. In a visible writing machine, pivoted type bars normally lying with their heads toward the front of the machine, a transverse bar, lever links pivoted at their front ends in said transverse bar upon axes in a straight transverse line with the pivoted portion of the links in a plane at right angles to the axis, the rear portions of the several links on each side of the longitudinal center of the machine being displaced laterally toward the center of the machine at angles which increase as the ends of the transverse bar are approached, links connecting the rear ends of the lever links and the heels of the type bars, pivoted key levers arranged in parallel series at right angles to the axes to the lever links, and substantially vertical links connecting the respective key levers with the corresponding lever links, the longer key levers being connected through the corresponding lever links at a different distance from their axes than the shorter key levers are connected through the corresponding lever links.

55. 26. In a single shift visible writing machine, a platen, a single type bar segment located in front of and below the platen, type bars pivoted therein with heads normally lying toward the front of the machine, lever links pivoted on a straight axis at right angles to the longitudinal center of the machine, said lever links having front pivotal portions at right angles to said axis, rear-

wardly extending portions displaced laterally toward the center of the machine according to their positions with respect to the type bar segment, links extending from the ends of the lever links to the type bars, pivoted key levers arranged below the lever links and substantially vertical links connecting the respective key levers with their corresponding lever links.

27. In a single shift visible writing machine, a platen, a single type bar segment located in front of and below the platen, type bars pivoted therein with their heads normally lying toward the front of the machine, lever links pivoted on a straight axis at right angles to the longitudinal center of the machine, said lever links having front pivotal portions at right angles to said axis, rearwardly extending portions displaced laterally toward the center of the machine, according to their positions with respect to the type bar segment, links extending from the ends of the lever links to the type bars, pivoted key levers arranged below the lever links and substantially vertical links connecting the respective key levers with their corresponding lever links, the lever links being of two different lengths and the longer and shorter lever links arranged in regular alternation.

28. In a single shift visible writing machine, a platen, a single type bar segment located in front of and below the platen, type bars pivoted therein with their heads normally lying toward the front of the machine, lever links pivoted on a straight axis at right angles to the longitudinal center of the machine, said lever links having front pivotal portions at right angles to said axis, rearwardly extending portions displaced laterally toward the center of the machine according to their positions with respect to the type bar segment, links extending from the ends of the lever links to the type bars, pivoted key levers arranged below the lever links and substantially vertical links connecting the respective key levers with their corresponding lever links, the lever links being of two different lengths and the longer and shorter lever links arranged in regular alternation, the longer key levers being connected to their corresponding lever links at a different distance from the axes of the latter than are the shorter key levers connected with their corresponding lever links.

In testimony whereof, we have hereunto subscribed our names.
